Primary Examiner — Susan Bennett Hattan*Assistant Examiner* — Barbara Lohr(74) *Attorney, Agent, or Firm* — Aka Chan LLP(57) **CLAIM**

The ornamental design for a sheet material with topographic pattern imprint, as shown and described.

DESCRIPTION

FIG. 1 shows a perspective view of a sheet material with topographic pattern imprint.

FIG. 2 shows a close-up view of the section indicated by circle 2 in FIG. 1.

FIG. 3 shows a top view of the design of FIG. 1; and, FIG. 4 shows a close-up cross-sectional view taken along line 4-4 in FIG. 3.

The broken lines depict the boundaries of the claimed design and form no part of the claimed design.
